COMBINED CONTAINER AND DISPENSER FOR HAIR ROLLERS

Raymond H. Board, 725 N. Pass Ave.,
Burbank, Calif. 91505

Filed June 19, 1969, Ser. No. 17,777

Term of patent 14 years

Int. Cl. D3—03

U.S. Cl. D86—10

FIGURE 1 is a perspective view of a combined container and dispenser for hair rollers, showing my new design;

I claim:

The ornamental design for a combined container and dispenser for hair rollers, substantially as shown.
